Patented May 5, 1914.

UNITED STATES PATENT OFFICE.

JOHN ONTKO, JR., OF SMITHFIELD, PENNSYLVANIA.

SHIP'S BUFFER.

1,095,919.

Specification of Letters Patent.

Patented May 5, 1914.

Application filed January 17, 1914. Serial No. 612,704.

To all whom it may concern:

Be it known that I, JOHN ONTKO, Jr., a subject of the Emperor of Austria-Hungary, residing at Smithfield, in the county of Fayette and State of Pennsylvania, have invented certain new and useful Improvements in Ships' Buffers, of which the following is a specification.

This invention relates to certain new and useful improvements in ships' buffers.

An object of the invention is to provide means at both sides, at the bow and at the stern of a boat or vessel, which will cushion the boat or vessel and protect same from injury by contacting with objects.

An embodiment of my invention is shown in the accompanying drawings, and will be described in detail, it being understood of course, that in the practice of the invention, various changes may be made in the details of construction without departing from the spirit of the invention as claimed.

In the drawings:—Figure 1 is a top plan view of a boat equipped with my improved buffer. Fig. 2 is a side elevation of the same, and, Fig. 3 is a transverse vertical sectional view on an enlarged scale and partly broken away.

In the illustrated embodiment of my invention, 5 designates the boat. At both sides, and at the front and rear of the boat, are arranged buffer plates spaced from and resiliently held away from the sides of the boat. These are preferably located at a point where they will be substantially on the water line, so as to be positioned at a point where any object would be liable to injure the boat by contact therewith.

The front buffer plate 6 is substantially V-shaped in form, the rear ends of same overlapping the forward ends of the side buffer plates 7, the rear ends of said buffer plates 7 overlapping the ends of the rear buffer plate 8, which latter is substantially

segment form. Between said buffer plates 45 and the outer face of the vessel hull are springs 9, suitably fastened as at 10 at their ends to the vessel hull and the buffer plates respectively. These springs serve to hold the buffer plates spaced away from the outer 50 face or wall of the vessel, and also serve to return the buffer plates to normal position after same have been forced inwardly by contact with an object.

The buffer plates are suspended from the 55 top or deck of the vessel hull by chains 11, and they are also tied at their lower edges by chains 12 to the keel or bottom of the boat. This serves to securely hold the buffer plates in the normal position and in a plane 60 parallel with the outer face or wall of the upper portion of the boat hull, as shown by Figs. 1 and 3 of the drawings.

Obviously, any injury to any one of the buffer plates can be repaired or a new buffer 65 plate substituted without interfering with or necessitating the removal of any of the other buffer plates.

Having fully described my invention, what I claim as new is:—

In a device of the character described, the combination with a vessel, of independent buffer plates for the opposite sides, the bow and the stern of said vessel, suspending chains connected to said plates and to the 75 deck of the vessel, securing chains connecting the lower edges of said plates to the bottom of the vessel, and springs arranged between said plates and the outer wall of the vessel for holding the plates spaced with 80 relation to said wall.

In testimony whereof I affix my signature in presence of two witnesses.

JOHN ONTKO, Jr.

Witnesses:

PETER VASIL,
HENLY DURKEES.
